AUTOMATIC FEED TYPEWRITER

Jack L. Kellerman, New York, N. Y., assignor, by
mesne assignments, to Joseph Zaretzki, New
York, N. Y.

Application May 28, 1940, Serial No. 337,620

6 Claims. (Cl. 197—126)

This invention relates to new and useful improvements in an automatic feed typewriter.

More specifically, the invention proposes an arrangement in a flat writing surface typewriter of the Elliott Fisher type, by which continuous forms and continuous carbon copies may be typewritten and simultaneously additional carbon copies made on tags, cards or sheets.

The invention is particularly intended for use in large mail order houses so that when the usual postal C. O. D. labels and copies are typed it is possible to make carbon copies of the typewritten material on the customary postal tags required on the C. O. D. packages. Heretofore it has been customary to use the C. O. D. labels and copies thereof in continuous forms and to separately type the necessary tags for the C. O. D. packages, because there was no prior method of holding and registering the forms and tags. In accordance with this invention the additional typing of the tags has been eliminated with a consequent saving of time and labor and possibility of error in copying.

More specifically the invention proposes the provision of a plate mounted on the platen beneath the forms which extend over the platen during the typing operation, and said plate to have an opening extending inwards from one side into which a card, or sheet, or tag may be engaged. It is also proposed that the plate have a top opening through which an area of said card, or sheet or tag is exposed. It is also contemplated to provide means for supporting carbon sheets between the forms being typed and across said card, sheet or tag so that the latter element will be simultaneously typed.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a plan view of the feed platen of a flat writing surface typewriter constructed in accordance with this invention and illustrated with continuous forms and carbon sheets.

Fig. 2 is a fragmentary enlarged vertical sectional view taken on the line 2—2 of Fig. 1.

Fig. 3 is a fragmentary enlarged vertical sectional view taken on the line 3—3 of Fig. 1.

Fig. 4 is a fragmentary view of a portion of Fig. 1 but illustrating the continuous forms and copies and carbon sheets removed.

Fig. 5 is a fragmentary vertical sectional view taken on the line 5—5 of Fig. 1.

The improvements in an automatic feed typewriter, in accordance with this invention, relate to improvements on the platen 10 of a typewriter of the Elliott Fisher type having a flat writing surface. The details of the typewriter will not be given in this specification as they form no part of the invention and the typing machines in question are generally known. The platen 10 is provided with the customary holding means at the front end 10a for holding the ends of continuous forms and copies 11 to be typed. The particular means shown on the drawing comprise a pair of pegs 12 projecting from the edge portion 10a of the platen 10 and engaging through openings 11a formed in the continuous forms and copies 11. A holding strip 13 extends across the edge portion 10a of the platen 10 and engages over the pegs 12 and the ends of the forms and copies 11. The strip 13 has openings 13a into which the pegs 12 project. The forms and copies 11 are imprinted as C. O. D. labels and copies, though this is merely by way of illustration since the invention may be applied to other types of forms and copies.

A plate 14 is fixedly mounted on the platen 10 beneath the continuous forms and copies 11. This plate 14 has an opening 14a extended inwards from one side 14b and adapted to receive and hold a card, sheet or tag 15. The plate 14 is also formed with a top opening 14c through which an area of the card, sheet or tag 15 is exposed.

Means is associated with the typewriter for supporting carbon sheets between the forms and copies 11 and across the said card, or sheet, or tag 15. As illustrated on the drawing this means comprises a roll of carbon material 16 having several superimposed web portions 16a, 16b and 16c, or layers, engaging in between the layers of the continuous forms and copies 11 and across the top of the plate 15. The roll 16 is mounted on a shaft 17 of the typewriter.

The free ends of the carbon sheets are releasably held by a lever 18. This lever is pivotally mounted at one of its ends by a pintle 19 upon the far side of the plate 14. The other end of the lever 18 is provided with a hook 18a which is engageable with a stud 20 mounted on the

plate 14. The lever 13 is of a sufficient length so that when the hook 13a is engaged on the stud 20 it must first be bowed slightly downwards, as illustrated in Fig. 5. This serves to tightly grip the ends of the carbon sheets. Fastening elements 21 in the form of small projections are arranged along the length of the lever 13 and are cooperative with niches 22 formed in the top of the plate 14 for assisting in more securely gripping and holding the carbon sheets.

The operation of the device is as follows:

When the continuous forms and copies 11 and the carbon sheets 16 are in the positions shown in Fig. 1, the typewriter may be operated to type the second from the bottom C. O. D. label illustrated in Fig. 1. The typing operation will cause carbon copies of the typed material to appear on the lower layers or copies of the continuous form and copies 11 and upon the card, sheet, or tag 15. It should be noted that the top opening 14c of the plate 14 is not as large as the top of the plate 14, or as the card, sheet or tag 15. Consequently it is possible to type certain material on the continuous forms 11 which is shielded from the card, sheet or tag 15. This arrangement is desirable in that material may be typed on the labels of the continuous forms and copies and this material will not be transferred to the tags. For example, a department, catalogue number, quantity, and description of the goods may be typed in on the label. It is obvious that this material must not appear on the tag.

The card 15 is then removed from the opening 14a of the plate 14 by pulling it sidewise. The typing machine is operated so that the holding strip 13 is lifted upwards, freeing the ends of the continuous forms 11. The continuous forms and copies 11 may now be pulled forwards so that the label and copies just typed are in position beneath the strip 13, which is then lowered to secure the continuous forms in the new position. A new card 15 is now inserted in the opening 14. Another C. O. D. label and copies may now be typed. In this manner any number of C. O. D. labels and copies may be typed. The finished labels and copies may be torn off from the end of the continuous forms and copies.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In an automatic feed typewriter, having a platen and holding means for supporting continuous forms and copies, a plate mounted on said platen beneath said forms and copies and having a side opening extending inwards from one side which is located in proximity to one of the sides of said continuous forms and copies into which a card or sheet or tag may be engaged and said plate having a top opening through which an area of said card or sheet or tag is exposed, and means for supporting carbon sheets between said forms and copies so as to extend from the side of said plate which is provided with said side opening across said card or sheet or tag, whereby said carbon sheets do not extend across the side of said plate which is provided with said side opening.

2. In an automatic feed typewriter, having a platen and holding means for supporting continuous forms and copies, a plate mounted on said platen beneath said forms and copies and having a side opening extending inwards from one side which is located in proximity to one of the sides of said continuous forms and copies into which a card or sheet or tag may be engaged and said plate having a top opening through which an area of said card or sheet or tag is exposed, and means for supporting carbon sheets between said forms and copies so as to extend from the side of said plate which is provided with said side opening across said card or sheet or tag, whereby said carbon sheets do not extend across the side of said plate which is provided with said side opening, said means comprising a rod to one side of said platen for supporting a roll of carbon sheets having several layers of carbon sheets for engaging between the forms mentioned, and means adjacent the other side of said forms and in proximity to said side of said plate which is provided with said side opening for releasably holding the free ends of said carbon sheets.

3. In an automatic feed typewriter, having a platen and holding means for supporting continuous forms and copies, a plate mounted on said platen beneath said forms and copies and having a side opening extending inwards from one side which is located in proximity to one of the sides of said continuous forms and copies into which a card or sheet or tag may be engaged and said plate having a top opening through which an area of said card or sheet or tag is exposed, and means for supporting carbon sheets between said forms and copies so as to extend from the side of said plate which is provided with said side opening across said card or sheet or tag, whereby said carbon sheets do not extend across the side of said plate which is provided with said side opening, said means comprising a rod to one side of said platen for supporting a roll of carbon sheets having several layers of carbon sheets for engaging between the forms mentioned, and means adjacent the other side of said forms and in proximity to said side of said plate which is provided with said side opening for releasably holding the free ends of said carbon sheets, comprising a lever mounted across the ends of the carbon sheets.

4. In an automatic feed typewriter having a platen and holding means for supporting continuous forms and copies, a plate mounted on said platen beneath said forms and copies and having a side opening extending inwards from one side which is located in proximity to one of the sides of said continuous forms and copies into which a card or sheet or tag may be engaged and said plate having a top opening through which an area of said card or sheet or tag is exposed, and means for supporting carbon sheets between said forms and copies so as to extend from the side of said plate which is provided with said side opening across said card or sheet or tag, whereby said carbon sheets do not extend across the side of said plate which is provided with said side opening, said means comprising a rod to one side of said platen for supporting a roll of carbon sheets having several layers of carbon sheets for engaging between the forms mentioned, and means adjacent the other side of said forms and in proximity to said side of said plate which is provided with said side opening for releasably holding the free ends of said

carbon sheets, comprising a lever mounted across the ends of the carbon sheets, and removable to permit the carbon sheets to be drawn out so that new carbon may be placed beneath the writing areas of the forms.

5. In an automatic feed typewriter having a platen and holding means for supporting continuous forms and copies, a plate mounted on said platen beneath said forms and copies and having a side opening extending inwards from one side which is located in proximity to one of the sides of said continuous forms and copies into which a card or sheet or tag may be engaged and said plate having a top opening through which an area of said card or sheet or tag is exposed, and means for supporting carbon sheets between said forms and copies so as to extend from the side of said plate which is provided with said side opening across said card or sheet or tag, whereby said carbon sheets do not extend across the side of said plate which is provided with said side opening, said means comprising a rod to one side of said platen for supporting a roll of carbon sheets having several layers of carbon sheets for engaging between the forms mentioned, and means adjacent the other side of said forms and in proximity to said side of said plate which is provided with said side opening for releasably holding the free ends of said carbon sheets, comprising a lever mounted across the ends of the carbon sheets, and removable to permit the carbon sheets to be drawn out so that new carbon may be placed beneath the writing areas of the forms, said lever being pivotally supported at one end and having a hook at its 35 other end engageable with a stationary stud.

10 15 20 25 30 35

6. In an automatic feed typewriter having a platen and holding means for supporting continuous forms and copies, a plate mounted on said platen beneath said forms and copies and having a side opening extending inwards from one side which is located in proximity to one of the sides of said continuous forms and copies into which a card or sheet or tag may be engaged and said plate having a top opening through which an area of said card or sheet or tag is exposed, and means for supporting carbon sheets between said forms and copies so as to extend from the side of said plate which is provided with said side opening across said card or sheet or tag, whereby said carbon sheets do not extend across the side of said plate which is provided with said side opening, said means comprising a rod to one side of said platen for supporting a roll of carbon sheets having several layers of carbon sheets for engaging between the forms mentioned, and means adjacent the other side of said forms and in proximity to said side of said plate which is provided with said side opening for releasably holding the free ends of said carbon sheets, comprising a lever mounted across the ends of the carbon sheets, and removable to permit the carbon sheets to be drawn out so that new carbon may be placed beneath the writing areas of the forms, said lever being pivotally supported at one end and having a hook at its other end engageable with a stationary stud, and gripping elements on said lever engageable against the material of said carbon sheets.

JACK L. KELLERMAN.
